PROTECTIVE APPARATUS

Application filed October 20, 1930. Serial No. 489,826.

This invention relates to electro-responsive devices and particularly to relays of the induction type.

The theory and manner of operation of induction-disc-type relays is well known to those versed in the art, and the problem of providing suitable time-operation characteristics for such relays has furnished a fertile field for research and development.

Load apparatus is usually designed to operate, for a limited time, under overload conditions, and relays have been designed accordingly to provide suitable operating characteristics. To secure apparatus or system protection, whereby limited overloads are permissible in order to take care of transient or small overload conditions, an operating characteristic is imparted to the relay such that a period of time will elapse before the relay contacts will close.

The provision of such operation characteristics for a relay prevents the closure of its contacts until some time interval has elapsed after the energizing current has exceeded a predetermined value. The apparatus or system to be protected may, therefore, be maintained in operation during transient or predetermined overload conditions.

In an induction-disc relay having a main energizing winding on one pole and a secondary winding on an adjacent pole, the torque exerted on the relay disc is proportional to the product of the main pole flux times the adjacent pole flux times the sine of the phase angle between them. The present invention embodies a novel means of providing a definite time characteristic for such a relay, or an induction-disc relay of any type. In order to obtain a definite time of operation, the product of the main pole flux times the adjacent or secondary pole flux times the sine of the angle between them must be maintained substantially constant for the operating range of the relay.

In accordance with the present invention, a torque-compensating means is utilized to predetermine the magnitude of current flow in the secondary winding of a relay. Obviously, changes in the magnitude of the current flowing in the secondary winding affects

the resultant torque acting upon the relay disc, and the relay contacts will not be closed until the end of a definite period of time after the current, in excess of a predetermined value, has passed through the relay.

To accomplish this, a torque compensator is electrically associated with the flux-producing windings of the relay and movably disposed with respect to the leakage-flux field of the main energizing winding.

The compensator comprises two windings wound in inductive relation upon a magnetic core, the primary winding thereof being connected in series with a secondary winding of the relay and, therefore, energized by a current in proportion to the current energization of the main winding of the relay. The secondary winding of the relay is wound on the same pole as the main energizing winding. Assuming this pole to be the lower pole of the relay, another secondary winding is disposed upon the upper pole of the said relay to cooperate with the main energizing winding to provide a rotating torque for a disc armature. The relay secondary winding is connected in series with the secondary winding of the torque compensator, and the current flowing through both of the windings is the same.

The torque compensator is adapted to be moved with respect to the main energizing winding to permit different values of the leakage flux of this winding to link with the torque compensator. The position of the compensator must be such that the leakage flux of the main energizing winding links the secondary winding of the torque compensator to decrease the effective flux linking that winding. In other words, the primary winding of the torque compensator is energized proportionally to the energization of the main winding of the relay, and the leakage flux of the main winding is caused to link the secondary winding of the torque compensator in a direction to oppose the flow of current in that winding. The changing of the amount of flux linkage with the secondary winding causes a corresponding change in the value of current flowing therein, and also the current flowing in the secondary relay.

winding, since the two windings are connected in series. The current through the relay secondary winding may thus be changed for any given condition by adjustment of the torque compensator, and the altering of the linking leakage-flux provides that the product of the fluxes of the relay windings and the sine of the angle between them may be made essentially constant for the operating range 10 of the relay.

The iron circuit of the torque compensator is designed to saturate for predetermined values of current flowing in its primary winding, and a constant value of current may, 15 therefore, be made to flow in the secondary winding of the torque compensator. From this, it may clearly be seen that the time-load curve of a compensated relay may be made lineal for predetermined values of current 20 energization of the relay.

The invention may best be understood by referring to the several figures of the drawing, wherein

Figure 1 is a view, in front elevation, of a 25 portion of a relay structure.

Fig. 2 is a view, in side elevation, corresponding to the arrangement shown in Fig. 1.

Fig. 3 is a bottom plan view of the arrangement shown in Figs. 1 and 2.

Fig. 4 is a schematic diagram of the electrical connections of the relay and compensator windings.

Fig. 5 is a detail diagram illustrating a 35 modification which utilizes a torque compensator of a different type.

Fig. 6 is a graphical illustration of characteristic time-load curves of a relay utilizing the present invention.

With more particular reference to Figs. 1, 40 2 and 3, an induction-disc relay is represented as having a core 11, comprising a plurality of iron laminations, and windings 12 and 13, associated with lower and upper core portions 14 and 16, respectively. The winding 45 12 constitutes the main energizing winding of the relay and a secondary winding, the two being schematically represented by the windings 12 and 12' in Fig. 4.

The flux produced by the main energizing 50 winding 12 combines with the fluxes produced by the secondary windings 13 to effect a rotating torque upon a disc armature 15 disposed between the core portions 14 and 16. It may be readily understood that the relay 55 structure, as represented in Fig. 1, 2 and 3, is merely diagrammatic and is to be considered as representative of an induction-disc relay of any type.

According to the present invention, a 60 torque compensator, comprising an iron circuit 17 and inductively related windings 18 and 19, is adjustably disposed with respect to the relay-energizing winding 12.

The iron circuit 17 comprises a plurality 65 of iron laminations which are secured to-

gether by means of machine screws 21, and the torque compensator, including the inductively related windings 18 and 19, is slidably mounted adjacent to the lower core structure of the relay by means of a supporting member 22 of U-shape and a guiding member 23.

The supporting member 22 and the guiding member 23 are securely mounted upon the lower portion of the core 11 by means of bolts 24, extending therethrough, and secured by means of nuts 26. The supporting member 22 is provided with a vernier screw 27 which is adapted to turn freely in its assembled position, as indicated in Figs. 2 and 3. One side of the torque compensator is provided with supporting members 28 of L-shape which are adapted to be moved, by the vernier screw 27, laterally with respect to the supporting member 22 and the core 11. The guide 23 is provided with a slot 29, suitable for guiding the ends of the supporting members 28 remote from the vernier screw 27.

By turning the vernier screw 27, the torque compensator may be moved laterally with respect to the core 11 and the main relay winding 12. As pointed out hereinbefore, the torque compensator is supported by the members 28 and is positioned by means of the vernier screw 27 and the guiding member 23.

Referring to Fig. 4, the main energizing winding 12 is wound upon the lower pole of a relay and is adapted to be energized in accordance with the current flowing in an alternating-current system. A secondary winding 12' is also wound on the lower pole of the core 11 and is serially connected with the primary winding 18 of the torque compensator. The secondary winding 19 of the torque compensator is serially connected with the relay secondary windings 13, and the currents through the said relay current windings is controlled by the amount of current permitted to flow in the secondary winding 100 of the torque compensator.

Assuming the instantaneous current flowing in the main relay winding 12 to be in a direction to produce an upward flux in the lower pole of the core 11, a current will be set up in the secondary winding 12' which is in a reverse direction with respect to the current flowing in the main winding 12. The current flowing in the secondary winding 12' also flows in the primary winding 18 of the torque compensator and generates a flux in the iron core 17. A secondary current is thereby generated in the secondary winding 19 of the torque compensator in a direction to oppose the inducing flux set up by the primary winding 18, and the current flowing in this secondary winding flows through the relay secondary windings 13.

Referring again to Fig. 2, the energizing current flowing in the main coil 12 sets up a 125 leakage flux around the coil and the lower

portion of the relay core 11. In accordance with the present invention, the torque compensator is movably positioned with respect to the energizing coil 12 and the core 11, so that, by placing the torque compensator adjacent to the main energizing winding 12, the leakage flux set up by the current flowing in the coil 12 is caused to link with the secondary winding 19 of the torque compensator. Obviously, the positioning of the torque compensator in its extreme right-hand position will permit the linkage of the greatest possible number of lines of leakage flux of the main energizing winding 12 with the secondary coil 19 of the torque compensator. The moving of the torque compensator to its left-hand position, or towards the front of the relay, decreases the effective linkage of the leakage flux of the main energizing winding 12, since the core 11 offers a better return path for the leakage flux than does the iron circuit of the torque compensator. It may be seen, therefore, that the movement of the torque compensator to various positions, by means of turning the vernier screw 27, causes a predetermined amount of leakage flux of the main energizing winding 12 to link the torque compensator, depending upon the degree of energization of the coil 12.

Assuming the current in the primary winding 18 of the torque compensator to be flowing in a direction to produce a magnetic flux in the iron circuit 17 in a clockwise direction, a current is induced in the secondary winding 19 which tends to oppose the flux producing it, as in a usual transformer. The positioning of the torque compensator in the leakage field of the main energizing winding 12 results in this leakage flux so linking the torque compensator as to oppose the magnetic flux set up in the torque compensator by the energization of its primary winding 18. It follows, therefore, that the more lines of leakage flux which are permitted to link with the torque compensator, the more the current in the secondary winding 19 will be reduced because of the bucking effect of this flux with respect to the magnetic flux produced by the primary winding 18.

By changing the value of current flowing in the secondary winding 19, the current flowing in the relay secondary windings 13 is also necessarily changed because these windings are connected in series. Since the torque produced by the relay windings 12 and 13 depends upon the value of current flowing therein, any change in the relay secondary current will result in a proportionate change in the relay torque.

The iron circuit 17 of the torque compensator is designed to saturate for predetermined values of current flow in the primary winding 18, in order to prevent the flow of current in the secondary winding 19 above a predetermined value. Thus, irrespective

of the degree of energization of the main energizing winding 12, the current permitted to flow in the secondary winding 19 of the torque compensator and in the secondary windings 13 of the relay is maintained constant above a predetermined value of current-flow in the main energizing winding 12. In addition to limiting the magnitude of current flowing in the secondary winding 19 by means of the saturation of the iron circuit 17, the torque compensator may be moved to permit the linkage of different values of leakage flux of the main energizing winding 12, thereby providing a vernier current adjustment for the secondary winding 19 and the relay secondary windings 13.

Referring to Fig. 6, the operation characteristics of a relay incorporating the present invention are plotted as a time-load curve. As indicated by curve 1, the torque compensator of the present invention provides a flat-curve characteristic which may be altered to that shown by curves 2 and 3, respectively, by permitting the torque compensator to be linked by more or less lines of the leakage flux of the main energizing winding 12.

It is quite obvious that the polarity of the secondary winding 19 of the torque compensator may be changed to permit the linkage of the leakage flux of the energizing winding 12 to add to the flux produced by the primary winding 18 of the torque compensator. In this manner, the relay may be provided with any desired inverse-time characteristic.

Fig. 5 represents a modified means of changing the torque exerted on the armature member of a relay. This scheme comprises, in effect, the shunting of part of the magnetic flux ordinarily allowed to react with the armature member.

A relay is diagrammatically shown as comprising a magnetic core 31 and a main energizing winding 32. The magnetic circuit 31 of the relay is provided with a phase-splitting means or short-circuiting turn 33 which cooperates with the magnetic flux set up in the main energizing winding 32 to effect a rotating flux on an armature disc 34. The armature disc 34 is mounted upon a spindle 36 which is supported by means of upper and lower jewel bearings 37 and 38, respectively.

The shunting means, which is provided for decreasing the effect of the relay magnetic flux, is represented as an iron member 39 which is adapted to be attracted toward the poles of the core member 31, against the action of a spring 41, whenever the current passing through the main energizing winding 32 exceeds a predetermined value. It may be seen, therefore, that the iron member 39 provides a magnetic shunt for some of the magnetic flux in the core member 31, and

the resulting torque, acting upon the disc member 34, may be maintained constant for a current energization of the main winding 32 above a predetermined value. Obviously, 5 the magnetic shunt 39 and the spring 41 may be designed to shunt predetermined values of the magnetic flux in the core member 31 for any given energization of the relay winding 32 and, therefore, the torque acting upon 10 the disc armature 34 may be maintained constant for such predetermined values of current energization.

Another means for maintaining a constant torque on a relay armature would be 15 to provide the usual main electromagnet, which saturates at high currents, and a small auxiliary electromagnet having a winding serially connected to the energizing winding of the main electromagnet and which does 20 not saturate at high current values. This auxiliary electromagnet would provide a torque acting in the opposite direction to the torque supplied by the main electro-magnet. In this manner, the time-load curve may be 25 adjusted to conform to a flat characteristic, as indicated in curve 1, Fig. 6.

As referred to hereinbefore, the present invention may be applied to any known relay structure in order to provide for predetermined torque conditions acting upon the relay armature to secure any time-load characteristic desired. Because of the novel feature of permitting the torque compensator to assume a dual role in providing a means 30 for flattening the time-load-curve characteristic of a relay, and in permitting different values of leakage flux of the main energizing winding of such a relay to link with the torque compensator, the present invention 35 constitutes a substantial improvement in the relay art.

In view of the novel and useful features included in the present invention, no limitations should be imposed thereon other than 40 such as may be imposed by the prior art and by the appended claims.

I claim as my invention:

1. In an induction-disc-type electro-responsive means, energizing means therefor 50 including primary and secondary windings, means movably associated with said primary winding for effecting a proportionate degree of energization of said secondary winding in accordance with the magnitude of 55 flux linkage between said primary winding and said associated means.

2. Torque-compensating means for an electro-responsive device having an armature, primary and secondary windings for 60 providing a torque for said armature, including winding means movably and magnetically associated with said primary winding.

3. In an electro-responsive means, an armature, primary and secondary windings for

effecting a rotating torque for said armature, and torque-compensating means movably and magnetically associated with said primary winding, including one winding electrically associated with said primary winding and another winding electrically associated with said secondary winding. 70

4. Means for predetermining the operating characteristic of an electro-responsive device having a rotatable armature and primary and secondary windings for producing a torque acting upon said armature, including a plural-winding means having one winding electrically associated with said primary winding and another winding electrically associated with said secondary winding, said plural-winding means being movably positioned with respect to said primary winding and adapted to be linked by the leakage 80 flux thereof. 85

5. An adjustable torque compensator for an electro-responsive device having an armature and torque producing windings associated therewith, including transforming 90 means electrically associated with said torque-producing windings, and means for movably positioning said transforming means with respect to one of said windings to permit a predetermined flux linkage of 95 said transformer means and the leakage flux of said winding.

6. In an electro-responsive device having an armature, primary and secondary windings associated therewith for producing a 100 torque on said armature, means for predetermining the torque exerted on said armature by said winding, including means movably positioned with respect to the leakage flux of 105 said primary winding, said means including a winding electrically associated with said primary and secondary windings.

7. In an electro-responsive device having an armature, primary and secondary torque-producing windings associated therewith, means for predetermining the time-operation 110 characteristics of said device including inductively related windings movably positioned with respect to said primary winding and adapted to be linked by leakage flux of 115 said primary winding, said inductively related winding being electrically associated with said primary and secondary windings and adapted to regulate the magnitude of current flow in said secondary winding. 120

8. In an induction-disc-type electro-responsive means including a main energizing means, winding means movably associated therewith and arranged to be linked by leakage flux thereof for predetermining the time element of operation of said electro-responsive means. 125

9. In an electro-responsive device, an armature, torque producing windings associated therewith including a main energiz- 130

ing winding and a secondary winding, and means for predetermining the magnitude of current flow in said secondary winding including inductive means electrically associated with said windings and movable with respect to said main energizing winding for predetermining the effective flux linkage of said inductive means with said main energizing winding.

10 In testimony whereof, I have hereunto subscribed my name this 15th day of October, 1930.

JOHN V. BREISKY.
